UNITED STATES PATENT OFFICE.

CLARENCE E. SMITH, OF NEW BRITAIN, CONNECTICUT.

CLASP OR FASTENER.

No. 807,403.

Specification of Letters Patent.

Patented Dec. 12, 1905.

Application filed February 11, 1905. Serial No. 245,211.

To all whom it may concern:

Be it known that I, CLARENCE E. SMITH, a citizen of the United States, residing at New Britain, Hartford county, Connecticut, have 5 invented certain new and useful Improvements in Clasps or Fasteners, of which the following is a full, clear, and exact description.

My invention relates to fasteners, and particularly to that class of fasteners comprising 10 two members which are hooked together and secured against accidental disengagement.

The object of the invention is to provide a simple and effective arrangement of parts whereby the article may be economically and 15 rapidly produced and easily and quickly operated.

While the invention has particular utility in connection with belts and straps, it is by no means limited to this special use, but may 20 be employed whenever a coupling device is needed.

In the accompanying drawings, Figure 1 is a plan view of the two members of my fastening device as they appear when hooked. 25 Fig. 2 is a longitudinal section showing the members in the unlocked position ready for disengagement. Fig. 3 is a plan view of one of the members detached. Fig. 4 is a cross-section on the line X X, Fig. 1, looking in 30 the direction of the arrow.

The fastening device will be seen to comprise two members, one of which will for convenience be termed the "hook" member and the other the "eye" member. The hook member is provided with a loop A, to which may be secured the fastening-strap. Obviously 35 the form of this loop is immaterial. Projecting forwardly of the loop A is the body B, which carries a rearwardly-extending hook 40 bill C, having at or near its forward side a locking enlargement D, preferably round or ball-like. In the specific form shown in the drawings this enlargement is connected to the body B by means of a contracted neck. The 45 eye member comprises a loop portion A', the function of which corresponds to the function of the loop portion A of the hook member. The eye portion may be formed of wire, bent to form the loop A' and the side bars E E and 50 the hook ends F F. These hook ends lie against or closely adjacent to one another, and the side bars intermediate the hook ends D and the loop A' are brought so close together as to form a passage of less diameter than the 55 diameter of the ball-like enlargement D of the hook member. The hook ends F F are

arranged in the same plane and when the parts are assembled engage underneath the bill C, while the ball-like enlargement D stands above the plane of the side arms E E, so that the 60 two members will be held against accidental disengagement. As will be seen upon reference to Fig. 2, the eye member shown at an angle relatively to the hook member is not yet in the final position. By pressing the eye 65 member down into the position indicated in dotted lines the side bars E E will spring apart to allow the ball-like head D to pass through, whereupon they will spring together underneath the head, and thus securely and effect- 70 ily hold the parts in said engaged position. In Fig. 4 it will be seen how the side bars ad- 75 jacent the head D engage underneath the same and prevent accidental detachment. This ac- 80 tion occurs because normally the space be- 85 tween the side arms E E adjacent to the en- largement D is slightly less than the greatest diameter of said enlargement. This arrange- 90 ment of parts is particularly advantageous for a variety of reasons. It substantially reduces 95 the cost of production and provides two de- 100 vices which have no separated or free ends which are liable to become entangled with companion parts during the manufacture or use of the same. 105

What I claim is—

1. In a clasp in combination, two coöperative detachable members, a hook borne by one of said members projecting rearwardly, a locking enlargement forward of said hook, the 90 other member comprising yielding side arms having hooked extremities, said hooks turn- 95 ing toward each other and arranged to engage the hooked portion of the first-mentioned member, the space between said side arms being normally less than the width of the lock- 100 ing enlargement.

2. In a clasp in combination, two coöperative detachable members, one of said members having a broad rearwardly-projecting hook 100 and a locking enlargement carried forwardly of said hook and in line therewith, the other member including two yielding side arms and having hooked extremities arranged to coöp- 105 erate with the hooked portion of the first-mentioned member, said side arms adjacent to the locking enlargement being arranged to engage on opposite sides thereof and under- 110 neath the same when the parts are assembled.

3. The combination of a member having a rearwardly-projecting retaining-bill and a locking enlargement adjacent thereto and for-

wardly projecting, of a second member comprising yielding side arms having hooked extremities arranged to engage said bill, said side arms being arranged to engage on each 5 side of said enlargement and snap over the same when said members are being connected.

4. The combination of a member having a rearwardly-projecting retaining-bill and a forwardly-projecting locking enlargement in 10 line therewith, of a second member including yielding side arms arranged to snap over the opposite sides of said locking enlargement when said members are being connected.

5. A hook member of a hook-and-eye clasp, 15 comprising, in a single piece of metal, a body portion, means at its rear end for fastening the hook member to a garment or other object, a centrally-disposed hook proper adapted to engage with the eye member of said clasp, 20 and a locking-head forward of said hook proper consisting of an enlargement over which the side members of the said eye must be sprung in order to effect an engagement of the two members of the said clasp, the said 25 enlargement connected with the body of said

hook member by a contracted neck, all substantially as described.

6. In a hook-and-eye clasp, in combination, 30 a hook member comprising a body portion having a centrally-disposed hook proper elevated above the plane of said body portion, means at its rear end for being attached to a garment, and at its forward end a locking-head elevated above the plane of said body portion and consisting of an enlargement connected with the said body portion by a contracted neck, of an eye member consisting of 35 a single length of resilient wire bent into loop form, the ends of the wire meeting in one end of said loop, one end of the loop adapted to 40 serve as the bow proper of said eye to engage the hook proper, the side arms of said eye adapted to engage with the locking-head, all substantially as set forth.

Signed at New Britain, Connecticut, this 45
9th day of February, 1905.

CLARENCE E. SMITH.
